UNITED STATES PATENT OFFICE.

HORATIO G. GILLMOR, OF BATH, MAINE.

RAIL-JOINT.

No. 909,177.

Specification of Letters Patent.

Patented Jan. 12, 1909.

Application filed February 12, 1906. Serial No. 300,667.

To all whom it may concern:

Be it known that I, HORATIO G. GILLMOR, a citizen of the United States, residing at Bath, county of Sagadahoc, State of Maine, have invented an Improvement in the Means of Forming Joints in Rails, of which the following is a specification accompanied by drawings.

This invention relates to railway joints, although the uses of the means employed to form the rail joints are not limited to such joints, for my invention may be used in any connection in which they may be found applicable.

One of the objects of my invention is to provide an efficient means of joining rails free from parts which may work loose after once having been properly placed.

Another object of my invention is to provide such support for the rail ends as to prevent deflections of the rail at the joint and thereby prevent the battering of the rail ends at the joint.

Another object of my invention is, in the cases where the rails are used as a portion of the electric circuit, to provide for an electrical conductivity through the joint as nearly as possible equal to or greater than the electrical conductivity of the unjointed portion of the rail.

Further objects of the invention will hereinafter appear, and to these ends the invention consists of a rail joint for carrying out the above objects embodying the features of construction, combination of elements and arrangement of parts having the general mode of operation substantially as herein-after described and claimed in this specification and shown in the accompanying drawings in which:—

Figure 1 is a plan view, partly in section, illustrating a form of the rail joint. Figs. 2 and 3 are, respectively, sections through the parts at the plane indicated by XX and YY in Fig. 1. Fig. 4 is a side elevation of the rail joint. Figs. 5 and 6 are a side and an end elevation, respectively, of a modified form of the rail joint. Figs. 8 and 7 are, respectively, a side elevation and a section of the parts at the plane indicated by XX of another modified form of the rail joint. Figs. 9 and 10 are, respectively, a section at the plane indicated by XX and a plan view, partly in section, of another modified form of the rail joint. Figs. 11 and 12

are, respectively, a section at the plane indicated by XX and a plan view, partly in section, of another modified form of the rail joint.

Similar letters refer to similar parts throughout the several views.

Referring to the drawings, A represents meeting ends of the rails supported in a chair D between the rising arms of which and the rail are driven the wedges B exerting pressure between the lower surfaces of the heads and the upper surfaces of the flanges of the rails. Shoulders F are formed on these wedges to bring up against the arms of the chair and act as stops to prevent the wedges from being driven farther than desirable. To draw the chair into intimate contact with the bases of the rails so that upward pressure will be exerted upon them, the wedges C are driven between B and the flanges at the top of the arms of the chair D. All the bearing surfaces are in this manner brought into close contact so that they exert pressure one upon the other and the relatively great depth of the joint as a whole in conjunction with the pressure of the bearing surfaces of its parts, gives it a strength and rigidity which enable it to withstand the stresses to which it is subjected in service without deflections or distortions of the rails or the parts of the joint. The pressure of the surfaces of contact of the rails with the parts of the joint is also a determining feature in the electrical conductivity at the joint; and, by providing for a suitable pressure between these surfaces of contact, the area of these surfaces as compared with the cross sectional area of the rail being great, the electrical conductivity through the joint may be made as great as or greater than that of the unjointed portion of the rail.

Where wedges are used in places subject to vibration they tend to slacken. It is necessary, therefore, to provide means for locking the wedges against any slackening movement once they are driven. It is necessary also in the rail joint to provide against movement of the joint as a whole with respect to the rails. These objects may be accomplished in a variety of ways. Among these is that illustrated in Figs. 1 to 4, inclusive, in which G represents the holes usually drilled in the webs of the rails near their ends. M is a recess in the face of B adjacent to the web of the rail and P is a recess in the

face of B adjacent to C. O is a groove formed in the face of C adjacent to B. O and P are formed in such positions in C and B that when the wedges have been driven to 5 position O and P will be adjacent; and P is given a sufficient length to allow for some variation in the relative positions of B and C, while O and P remain adjacent. With the wedges in position O and P then form 10 a gate, through which by suitable passages R and N formed in B, molten metal may be introduced to and fill the spaces L, G, M, N, R, O, and P and all interstices of the joint; suitable means being employed if desired to 15 prevent the molten metal from filling the space between the rail ends; to keep this space free to provide for the changes in length of the rails on account of changes in temperature. The metal so introduced when 20 solidified effectually prevents movement of the parts of the joint with respect to one another. By heating the joint suitably before pouring the molten metal and by employing a metal which melts at a comparatively 25 low temperature and raising its temperature considerably beyond the melting temperature, all of the interstices of the joint may be filled. It will be understood that in introducing the molten metal the openings 30 between the rails and the other parts of the joint will be suitably fitted. In addition to retaining the parts of the joint in position the solidified metal, filling all the interstices of the joint, will add materially to its rigidity; and, by increasing the areas of contact 35 and cross section in the joint, will greatly increase its electrical conductivity. Furthermore, the filling of the interstices of the joint in this manner excludes from the surfaces of 40 contact of the parts of the joint the corroding agents which might tend to decrease the electrical conductivity at such surfaces.

In Figs. 5 and 6 the forms of the parts B and C are modified, so that while B₃ and 45 C₁, together perform the same functions as B and C in Figs. 1 to 4 inclusive; by forming complementary wedging surfaces in the two parts B₃ and C₁, combined they have exterior parallel surfaces and the wedging 50 forces exerted when C₁ is driven into position secure the desired upward pressures under the heads of the rails; and, through the chair or clamp D, under the bases of the rails, the downward pressures upon the upper 55 surfaces of the flanges of the rails. The parts B₃ and C₁ are arranged to interlock, automatically, at E, a catch projection being formed in B₃ and a series of teeth in a light arm, 1, extending from C₁. As C₁ is driven 60 into position this arm springs sufficiently to allow a tooth to pass the catch projection and the resilience of the materials causes the arm to return so that a tooth and the catch projection interlock at E when the proper position 65 has been reached. Molten metal is in-

roduced in a manner similar to that described above to give rigidity to the joint and lower its electrical resistance.

In Figs. 7 and 8 a fish bar of the usual type is employed on the side of the rail upon 70 which the wheel flanges would come with the rail in service and one arm of the chair D is formed to engage directly with this fish bar. The parts at the other side of the joint are similar to those in Figs. 5 and 6 except 75 that C₁ is provided with a slotted aperture to take a pin G₂ which passes through the hole G in the rail and the hole in the fish bar B₂; and B₃ is driven to position. To secure the wedges in place B₃ is constructed with a 80 catch projection which springs the arm of D as B₃ is driven to position and automatically interlocks with the arm of D, by the resilience of the materials, when B₃ reaches the proper position. The base plate K is notched for 85 the arms of the chair D and is provided with spiking apertures to receive the spikes H. Those on the side upon which the fish bar B₂ is register with the notches for these spikes in the fish bar. As shown in Fig. 8, 90 the interstices of the joint are filled with molten metal in the manner described when referring to Figs. 1 to 4 inclusive.

In the modified form of the joint shown in Figs. 9 and 10 a fish bar B₁ of special form 95 is employed on the side of the rail upon which the wheel flanges would come when the rails are in service and the chair is modified correspondingly. The bar B₁ is formed with lugs G₁ which engage with the holes 100 in the rails to prevent longitudinal movement of B₁ with respect to the rail and the projections F near the ends of B₁ prevent longitudinal movement of the chair D with respect to B₁; and, therefore, movement of 105 the joint with respect to the rail. The chair D is formed with an extended base K, arranged to rest upon two ties and this base has spiking apertures to take the spikes H. The wedges B and C on the side of the 110 rails opposite to B₁ are in all respects similar to the same parts in Figs. 1 to 4. To provide for the locking of these wedges in position when they have been driven to place, the wedge C is designed to interlock at E 115 with the chair D. A catch projection is formed on D and the wedge C is formed with a number of teeth the edges of which lie about in the plane of the top face of the wedge. As the wedge is driven to position 120 the projection D is forced out sufficiently to permit a tooth of C to pass and when the proper position is reached a tooth of the wedge and the projection of the chair interlock at E by the resilience of the materials 125 used. The use of molten metal to fill all the spaces between the rails and the other parts of the joint as shown insures rigidity and low electrical resistance.

In Figs. 11 and 12 ordinary fish bars B₂ 130

and wedges B_3 are employed. The pins G_2 are inserted in the holes G in the rail and in the fish bars to prevent longitudinal movement of these with respect to the rail. To hold the rails securely against creeping a base plate K , notched to take the arms of the chair D so as to prevent the movement of one relative to the other is employed, and is provided with spiking apertures registering with the notches in the fish bars B_2 . The base plate K and fish bars are long enough to rest upon two ties and the spikes H , engaging with the notches in B_2 and traversing the spiking apertures in K , effectually secure the rail and joint. The parts B_3 and C_1 are entirely similar in function to parts of the same designations in Figs. 5 to 8, inclusive, and B_4 differs from B in the other figures by providing only for the vertical wedging action of C . The securing of the wedges in place is provided for by catch projections on C_1 and C which automatically interlock with the flange of D when C_1 and C are driven to the proper position, and the introduction of molten metal as described above and illustrated in the figures.

Obviously some features of this invention may be used without others and the invention may be embodied in widely varying forms of which those shown in the drawings are but a few of the types.

Therefore without limiting the invention to the constructions shown and described nor enumerating the equivalents, I claim and desire to secure by Letters Patent the following:

1. A wedge clamp; comprising a clamp body with suitably formed, upwardly extending, arms, one of the said arms being overturned inwardly at its upper edge; and a pair of wedges, constructed with wedging surfaces to engage with each other, other bodies, and the said inwardly-overturned portion of an arm of the clamp body, to secure pressure, in two directions approximately at right angles, between the clamp and the said bodies; for substantially the purposes set forth.

50 2. A wedge clamp; comprising a clamp body with suitably formed, upwardly extending, arms, one of the said arms being overturned inwardly at its upper edge; a pair of wedges, constructed with wedging surfaces to engage with each other, other bodies, and the said inwardly-overturned portion of an arm of the clamp body, to secure pressure, in two directions approximately at right angles, between the clamp and said bodies; and means to prevent movement of the wedges with respect to each other and the said clamp body; for substantially the purposes set forth.

65 3. A wedge clamp; comprising a clamp body with suitably formed, upwardly ex-

tending, arms, overturned inwardly at their upper edges; wedges, constructed with wedging surfaces to engage, in pairs, with each other, other bodies, and the said inwardly-overturned portions of the arms of the clamp 70 body, to secure pressure, in two directions approximately at right angles, between the clamp and the said bodies; for substantially the purposes set forth.

4. A wedge clamp; comprising a clamp 75 body, with suitably formed, upwardly extending, arms, overturned inwardly at their upper edges; wedges, constructed with wedging surfaces to engage, in pairs, with each other, other bodies, and the said inwardly-overturned portions of the arms of the clamp 80 body, to secure pressure, in two directions approximately at right angles, between the clamp and the said bodies; and means to prevent movement of the said wedges with 85 respect to each other and the said clamp body; for substantially the purposes set forth.

5. A rail joint; comprising the rails; a chair, having suitably formed upwardly extending arms with inwardly projecting flanges thereon; and wedges, constructed to engage with the rails, the chair and with each other, in pairs, to secure an upward pressure 90 of the parts of the joint under the heads and the lower surfaces of the bases of the rails and a downward pressure of the parts of the joint 95 upon the upper surfaces of the bases of the rails; for substantially the purposes set forth.

6. A rail joint; comprising the rails; a chair having suitably formed upwardly extending arms with inwardly projecting flanges thereon; wedges, constructed to engage with the rails, the chair and with each other, in pairs, to secure an upward pressure 100 of the parts of the joint under the heads and the lower surfaces of the bases of the rails and a downward pressure of the parts of the joint upon the upper surfaces of the bases of the rails; and means to prevent the movement 105 of the wedges with respect to each other and the other parts of the joint; for substantially the purposes set forth.

7. A rail joint; comprising the rails; a chair, having suitably formed upwardly extending arms with inwardly projecting flanges thereon; wedges, constructed to engage with the rails, the chair and with each other, in pairs, to secure an upward pressure 115 of the parts of the joint under the heads and the lower surfaces of the bases of the rails and a downward pressure of the parts of the joint upon the upper surfaces of the bases of the rails; means to prevent movement of the wedges with respect to each other and the 120 other parts of the joint; and means to prevent longitudinal movement of one rail with respect to the chair and wedges; for substantially the purposes set forth.

8. A rail joint; comprising the rails; a 130

- chair, having suitably formed upwardly extending arms with inwardly projecting flanges thereon; wedges, constructed to engage with the rails, the chair and with each other, in pairs, to secure an upward pressure of the parts of the joint under the heads and the lower surfaces of the bases of the rails and a downward pressure of the parts of the joint upon the upper surfaces of the bases of the rails; means to prevent movement of the wedges with respect to each other and the other parts of the joint; means to prevent longitudinal movement of one rail with respect to the chair and wedges; and a base plate, interlocking with the chair and extending transversely for a portion of its length beyond the edges of the bases of the rails and provided with spiking apertures; for substantially the purposes set forth.
- 20 9. A rail joint; comprising the rails; a fish bar; a chair, comprising a base and two upwardly extending arms, the said arms being constructed with inwardly projecting flanges; wedges, constructed to engage, in pairs, with each other, the chair and the other parts of the joint to secure an upward pressure under the heads and the lower surfaces of the bases of the rails and a downward pressure of the parts of the joint upon the upper surfaces of the bases of the rails; for substantially the purposes set forth.
- 10 10. A rail joint; comprising the rails; a fish bar; a chair, comprising a base and two upwardly extending arms, the said arms being constructed with inwardly projecting flanges; wedges, constructed to engage, in pairs, with each other, the chair and the other parts of the joint to secure an upward pressure of the parts of the joint under the heads and lower surfaces of the bases of the rails and a downward pressure of the parts of the joint upon the upper surfaces of the bases of the rails; and means to prevent movement of the wedges with respect to each other and the other parts of the joint; for substantially the purposes set forth.
- 25 11. A rail joint; comprising the rails; a fish bar; a chair, comprising a base and two upwardly extending arms, the said arms being constructed with inwardly projecting flanges; wedges, constructed to engage, in pairs, with each other, the chair and the other parts of the joint to secure an upward pressure under the heads and lower surfaces of the bases of the rails and a downward pressure upon the upper surfaces of the bases of the rails; means to prevent movement of the wedges with respect to each other and other parts of the joint; and means to prevent longitudinal movement of one rail with respect to the fish bar, chair and wedges; for substantially the purposes set forth.
- 30 12. A rail joint; comprising the rails; a fish bar, a chair, comprising a base and two upwardly extending arms, the said arms be-

ing constructed with inwardly projecting flanges; wedges, constructed to engage, in pairs, with each other, the chair and other parts of the joint to secure an upward pressure under the heads and lower surfaces of the bases of the rails and a downward pressure upon the upper surfaces of the bases of the rails; means to prevent movement of the wedges with respect to each other and other parts of the joint; means to prevent longitudinal movement of one rail with respect to the fish bar, chair and wedges; and a base plate, interlocking with the chair, and extending transversely for a portion of its length beyond the edges of the bases of the rails and provided with spiking apertures; for substantially the purposes set forth.

13. A rail joint; comprising the rails; fish bars; a chair, comprising a base and two upwardly extending arms, the said arms being constructed with inwardly projecting flanges; wedges, constructed to engage in pairs with each other, the chair and other parts of the joint to secure an upward pressure under the heads and the lower surfaces of the bases of the rails and a downward pressure of the parts of the joint upon the upper surface of the bases of the rails; for substantially the purposes set forth.

14. A rail joint; comprising the rails; fish bars; a chair, comprising a base and two upwardly extending arms, the said arms being constructed with inwardly projecting flanges; wedges, constructed to engage in pairs with each other, the chair and other parts of the joint to secure an upward pressure of the parts of the joint under the heads and lower surfaces of the bases of the rails and a downward pressure of the parts of the joint upon the upper surfaces of the bases of the rails; and means to prevent movement of the wedges with respect to each other and the other parts of the joint; for substantially the purposes set forth.

15. A rail joint; comprising the rails; fish bars; a chair, comprising a base and two upwardly extending arms, the said arms being constructed with inwardly projecting flanges; wedges, constructed to engage in pairs with each other, the chair and other parts of the joint to secure an upward pressure under the heads and lower surfaces of the bases of the rails and a downward pressure of the parts of the joint upon the upper surfaces of the bases of the rails; means to prevent movement of the wedges with respect to each other and the other parts of the joint; and means to prevent longitudinal movement of one rail with respect to the fish bars, chair and wedges; for substantially the purposes set forth.

16. A rail joint; comprising the rails; fish bars; a chair, comprising a base and two upwardly extending arms, the said arms being constructed with inwardly projecting flanges;

wedges constructed to engage in pairs with each other, the chair and other parts of the joint to secure an upward pressure of the parts of the joint under the heads and lower surfaces of the bases of the rails and a downward pressure of the parts of the joint upon the upper surfaces of the bases of the rails; means to prevent movement of the wedges with respect to each other and the other parts 5 of the joint; means to prevent longitudinal movement of one rail with respect to the fish bars and chair; and a base plate, interlocking with the chair, extending transversely for a portion of its length beyond the edges of 10 the bases of the rails and provided with spiking apertures; for substantially the purposes set forth.

17. A rail joint; comprising the rails; a chair, having suitably formed arms; a wedge 20 or wedges, constructed to exert wedging forces between the rails and the said chair; and a metallic filler introduced in a molten condition to the spaces between the said wedge or wedges and other parts of the joint; for substantially the purposes set forth.

18. A rail joint; comprising the rails; a chair having suitably formed arms; a base plate, contacting with the bases of the rails, interlocking with the said chair; a wedge, or 30 wedges, constructed to exert wedging forces between the rails and the said chair; and a metallic filler introduced in a molten condition to the spaces between said wedge and other parts of the joint; for substantially the 5 purposes set forth.

19. A rail joint; comprising the rails; a fish bar or fish bars; a chair having suitably formed arms; a wedge, or wedges, constructed to exert wedging forces between the chair 40 and other parts of the joint; and a metallic filler introduced in a molten condition to the interstitial spaces between the parts of the joint; for substantially the purposes set forth.

20. A rail joint; comprising the rails; a fish bar or bars; a base plate contacting with the base of the said rails; a chair having suitably formed arms interlocking with the said base plate; a wedge, or wedges, constructed 50 to exert wedging forces between the chair and the other parts of the joint; and a metallic filler introduced in a molten condition to the interstitial spaces between the parts of the joint; for substantially the purposes set forth.

21. A rail joint; comprising the rails; a chair, having suitably formed, upwardly projecting, arms, one of which is overturned inwardly at its upper edge; wedges, constructed 60 to engage with the rails, the chair and with each other, to secure an upward pressure under the heads and lower surfaces of the bases of the rails and a downward pressure upon the upper surfaces of the bases of the rails; and a metallic filler, introduced in a 65

molten condition to the spaces between the said wedges and other parts of the joint; for substantially the purposes set forth.

22. A rail joint; comprising the rails; a base plate, contacting with the bases of the 70 rails; a chair, having suitably formed, upwardly projecting arms, interlocking with the said base plate, one of the said arms being overturned inwardly at its upper edge; wedges constructed to engage with the rails, 75 the chair and with each other, to secure an upward pressure under the heads and lower surfaces of the bases of the rails and a downward pressure upon the upper surfaces of the bases of the rails; and a metallic filler introduced in a molten condition to the spaces between the said wedges and other parts of the joint; for substantially the purposes set forth.

23. A rail joint; comprising the rails; a chair having suitably formed arms, overturned inwardly at their upper edges; wedges, constructed to engage with the rails, the chair and each other, in pairs, to secure an upward pressure under the heads and lower surfaces of the bases of the rails and a downward pressure upon the upper surfaces of the bases of the rails; and a metallic filler introduced in a molten condition to the spaces between the said wedges and other parts of the joint; for substantially the purposes set forth.

24. A rail joint; comprising the rails; a base plate, contacting with the bases of the said rails; a chair, having suitably formed arms overturned inwardly at their upper edges, interlocking with the said base plate; 100 wedges, constructed to engage with the rails, the chair and each other, in pairs, to secure an upward pressure under the heads and lower surfaces of the bases of the rails and a downward pressure upon the upper surfaces of the bases of the rails; and a metallic filler introduced in a molten condition to the spaces between the said wedges and other parts of the joint; for substantially the purposes set forth.

25. A rail joint; comprising the rails; a fish bar or fish bars; a chair, having suitably formed upwardly projecting arms, one of which is overturned inwardly at its upper edge; wedges constructed to engage with each other, the chair and other parts of the joint, to secure an upward pressure of the parts of the joint under the heads and lower surfaces of the bases of the rails, and a downward pressure of the parts of the joint upon the upper surfaces of the bases of the rails; and a metallic filler introduced in a molten condition to the interstitial spaces between the parts of the joint; for substantially the purposes set forth.

26. A rail joint; comprising the rails; a fish bar or fish bars; a base plate, contacting with the bases of the rails; a chair, having suitably formed, upwardly projecting arms, one of which is overturned inwardly at its 130

upper edge, interlocking with the said base plate; wedges, constructed to engage with the chair, other parts of the joint and each other, to secure an upward pressure of the parts of the joint under the heads and lower surfaces of the bases of the rails, and a downward pressure of the parts of the joint upon the upper surfaces of the bases of the rails; and a metallic filler introduced in a molten condition to the interstitial spaces between the parts of the joint; for substantially the purposes set forth.

27. A rail joint; comprising the rails; fish bars; a chair having suitably formed, upwardly projecting arms, overturned inwardly at their upper edges; wedges constructed to engage with the chair, other parts of the joint and each other, in pairs, to secure an upward pressure of the parts of the joint under the heads and lower surfaces of the bases of the rails, and a downward pressure of the parts of the joint upon the upper surfaces of the bases of the rails; and a metallic filler introduced in a molten condition to the interstitial spaces between the parts of the joint; for substantially the purposes set forth.

28. A rail joint; comprising the rails; fish bars; a base plate contacting with the base of the rails; a chair having suitably formed, upwardly projecting arms, overturned inwardly at their upper edges, interlocking with the said base plate; wedges, constructed to en-

gage with the chair, other parts of the joint and each other in pairs, to secure an upward pressure of the parts of the joint under the heads and lower surfaces of the bases of the rails, and a downward pressure of the parts of the joint upon the upper surfaces of the bases of the rails; and a metallic filler introduced in a molten condition to the interstitial spaces between the parts of the joint; for substantially the purposes set forth.

29. A rail joint, including, in combination with the rails, a chair having an upwardly projecting arm, a wedge driven in between said chair arm and said rails and a metallic filler introduced in fluid condition to the spaces between the several parts of the joint, substantially as described.

30. The combination of rails and a joint for the adjacent ends thereof, including a chair having an upwardly projecting arm with an inwardly projecting flange, wedges driven in between said chair arm and said rails and a metallic filler introduced in molten condition to the spaces between the several parts of the joint.

In testimony whereof I have signed this specification in the presence of two subscribing witnesses.
